[57] CLAIM

The ornamental design for a shower splash guard, as shown and described.

DESCRIPTION

FIG. 1 is a perspective view of a shower splash guard showing my new design;

FIG. 2 is a front elevational view, the rear view being a mirror image thereof;

FIG. 3 is a cross-sectional view thereof taken along lines 3—3 of FIG. 2;

FIG. 4 is an end view thereof; and,

FIG. 5 is a cross-sectional view thereof taken along lines 5—5 of FIG. 2.

The broken line showing is for illustrative purposes only and forms no part of the claimed design.
